DESIGN FOR COMBINED SNOW PANTS AND VEST

Irving Gerstman, Buffalo, N. Y.

Application July 26, 1944, Serial No. 114,559

Term of patent 14 years

(Cl. D3—17)

To all whom it may concern:

Be it known that I, Irving Gerstman, a citizen of the United States, residing at Buffalo, in the county of Erie and State of New York, have invented a new, original, and ornamental Design for Combined Snow Pants and Vest, of which the following is a specification, reference being had to the accompanying drawing, forming part thereof.

In the drawing:

Fig. 1 is a perspective view, viewed from the rear, of combined snow pants and vest embodying my new design and showing the side slide fastener and buttoned shoulder open to permit of putting the garment on.

Fig. 2 is a similar view showing the side slide fastener closed and the shoulder buttoned.

The front of the garment which is not shown is substantially similar to the back shown in the figures.

I claim:

The ornamental design for combined snow pants and vest, as shown and described.

IRVING GERSTMAN.
